United States Patent Office.

JAMES S. KIRK, OF CHICAGO, ILLINOIS.

Design No. 3,944, dated March 29, 1870.

DESIGN FOR A TRADE-MARK.

The Schedule referred to in these Letters Patent and making part of the same

To all whom it may concern:

Be it known that I, JAMES S. KIRK, of the city of Chicago, in the county of Cook and State of Illinois, have invented and produced a new and original Design for a "Trade-Mark;" and I do hereby declare that the following is a full, clear, and exact description thereof, reference being had to the accompanying print of my trade-mark.

My design consists of a card or label, in the center of which is placed a design consisting of three concentric circles. The space between the interior and the middle circles is filled with the words "trade-mark," above, and with two sheaths of wheat connected together below.

The inside space of the interior circle is occupied with a shield, containing a "diamond K," in the center, a weighing-scale above, and a small shield placed between two laurel-branches below the "diamond K," the small shield having a row of five stars placed horizontally in its upper part, the lower part being filled with vertical stripes.

From the space between the outside and the middle circles in the direction of the horizontal diameter, and on both sides of the said circles, come out to the right and left two rolls or flaps, one on each side of the said concentric circles, one of which rolls or flaps bearing the number and word "60 bars," and the other the number and word "60 lbs."

The above-described design placed in the center of the label or card is surmounted by the words, printed in conspicuous characters "Savon Imperial."

Below the design can be placed the name and the place of the manufacturers.

What I claim as my invention and desire to secure by Letters Patent, is—

The trade-mark, consisting of the design as herein described, and of the words "savon imperial," all arranged substantially as and in the manner set forth.

JAMES S. KIRK.

Witnesses:

J. B. TURCHIN,
W. MILTON KIRK.
